UNITED STATES PATENT OFFICE

101,910

DESIGN FOR A FOUNTAIN PEN HOLDER DESK UNIT

David Williams, Beverly Hills, Calif., assignor to
W. A. Sheaffer Pen Company, Fort Madison,
Iowa, a corporation of Delaware

Application May 13, 1935, Serial No. 56,797

Term of patent 3½ years

To all whom it may concern:

Be it known that I, David Williams, a citizen of the United States, residing at Beverly Hills, in the county of Los Angeles and State of California, have invented a new, original, and ornamental Design for a Fountain Pen Holder Desk Unit, of which the following is a specification, reference being had to the accompanying drawing, forming a part thereof.

Fig. 1 is a perspective view of a fountain pen holder desk unit showing my new design, the dominant features of which comprise a pair of cylinders having opposed longitudinally extending peripheral V-shaped grooves for supporting a substantially flat base; and

Fig. 2 is a rear elevation of the same.

I claim:

The ornamental design for a fountain pen holder desk unit, substantially as shown and described.

DAVID WILLIAMS.
